DESIGN FOR A PARKING METER HOUSING

Herman S. Johns, Oklahoma City, Okla., assignor
to Wiley W. Lowrey, Oklahoma City, Okla.

Application July 31, 1937, Serial No. 70,763

Term of patent 14 years

To all whom it may concern:

Be it known that I, Herman S. Johns, a citizen of the United States of America, residing at Oklahoma City, in the county of Oklahoma and State of Oklahoma, have invented a new, original, and ornamental Design for Parking Meter Housings, of which the following is a specification, reference being had to the accompanying drawing, forming part thereof.

Figure 1 is an enlarged isometric view of the lower portion of the housing,

Figure 2 is an elevation of the housing,
Figure 3 is an enlarged isometric view of the upper portion of the housing, and

Figure 4 is a view similar to Figure 3, showing the side diametrically opposite of that shown in Figure 3.

I claim:

The ornamental design for a parking meter housing, as shown.

HERMAN S. JOHNS.
